Harry C. Schroeder,
attorney.

UNITED STATES PATENT OFFICE.

JAMES C. EWING, OF OAKLAND, CALIFORNIA.

PYJAMAS.

Application filed January 31, 1921. Serial No. 441,255.

To all whom it may concern:

Be it known that I, JAMES C. EWING, a citizen of the United States, residing at Oakland, in the county of Alameda and State of California, have invented certain new and useful Improvements in Pyjamas, of which the following is a specification.

My invention relates to improvements in pyjamas constructed without buttons or other like fastening means so that they may be readily slipped on and off.

Referring to the annexed drawing in which my invention is illustrated and which forms a part of this specification:

15 Figure 1 is a front view of the jacket of my pyjamas.

Figure 2 is a front view of the trousers of my pyjamas with the fly closed.

20 Figure 3 is a front view of the trousers with the fly partly open.

In the drawing 1 indicates the trousers and 2 the jacket of my pyjamas. The trousers have a fly 3 without buttons which is held closed by a draw string 4 extending

through a hem 5 around the upper edge or 25 waist of the trousers, said draw string being also adapted to hold up the trousers on the wearer. The draw string is tied in front as shown in Figure 2. The jacket 2 is not separated vertically in front or back, but 30 has a head opening 6 in the top, which opening is cut a little low to a point 7 in front and is large enough to allow the head of the wearer to pass therethrough comfortably to 35 slip on or off the jacket. The jacket has 35 loose sleeves 8.

Having described my invention, I claim:

In a pyjamas trousers having a fly extending to the upper edge of said trousers, a hem around the waist and on the inside of 40 said trousers, a draw string extending through said hem, the ends of the hem being located at a distance from the top of the fly so that the ends of the draw string may be tied together on the inside of the garment. 45

In testimony whereof I affix my signature.

JAMES C. EWING.
